WATER COLOR PALETTE

Joseph E. Knowles, Goode P. Davis, and Standish Backus, Jr., Santa Barbara, Calif.

Application March 26, 1949, Serial No. 1,636

Term of patent 14 years

(Cl. D74—1)

To all whom it may concern:

Be it known that we, Joseph E. Knowles, Goode P. Davis, and Standish Backus, Jr., citizens of the United States, residing at Santa Barbara, in the county of Santa Barbara and State of California, have invented a new, original, and ornamental Design for Water Color Palettes, of which the following is a specification, reference being had to the accompanying drawings, forming part thereof.

Figure 1 is a top plan view of a water color palette showing our new design in closed position.

Figure 2 is a side elevational view of Figure 1.

Figure 3 is a bottom plan view of Figure 1.

Figure 4 is a front end view thereof.

Figure 5 is a rear end view thereof in open position.

Figure 6 is a perspective view thereof in open position.

The side not shown is substantially the same as the one shown.

We claim:

The ornamental design for a water color palette, as shown and described.

JOSEPH E. KNOWLES.
GOODE P. DAVIS.
